US00D545159S

(12) **United States Design Patent** (10) **Patent No.:** **US D545,159 S**
(45) **Date of Patent:** **** Jun. 26, 2007**

(54) **BATTERY-OPERATED DRILLING SCREWDRIVER**

(75) Inventors: **Klaus Schoen**, Altbach (DE); **Michalis Stefanopoulos**, Solothurn (CH); **Daniel Brogli**, Arlesheim (CH)

(73) Assignee: **Robert Bosch GmbH**, Stuttgart (DE)

(**) Term: **14 Years**

(21) Appl. No.: **29/254,025**

(22) Filed: **Feb. 16, 2006**

Related U.S. Application Data

(63) Continuation-in-part of application No. 29/131,457, filed on Oct. 20, 2000, now abandoned.

(30) **Foreign Application Priority Data**

Apr. 20, 2000 (DE) 400 04 019

(51) **LOC (8) Cl.** **08-01**

(52) **U.S. Cl.** **D8/68**

(58) **Field of Classification Search** ..... D8/14.1, D8/61, 62, 63, 64, 65, 66, 67, 68, 69, 70; 81/57.11, 429, 464, 465, 466, 469, 489; 173/13, 173/104, 114, 168, 169, 170, 171, 178, 201, 173/211, 213, 217; 408/20, 124, 125, 234, 408/241 R; 451/358; 310/50; 227/8, 113, 227/114, 120, 130, 136, 142

(57) **CLAIM**

The ornamental design for a battery-operated drilling screwdriver, as shown and described.

DESCRIPTION

FIG. 1 is a side view of a battery-operated drilling screwdriver showing my new design;

FIG. 2 is the opposite side of FIG. 1 thereof;

FIG. 3 is a front view thereof;

FIG. 4 is a rear view thereof;

FIG. 5 is a top view thereof;

FIG. 6 is a bottom view thereof;

FIG. 7 is a side view of an alternate embodiment of my design;

FIG. 8 is the opposite side of FIG. 7 thereof;

FIG. 9 is a front view thereof;

FIG. 10 is a rear view thereof;

FIG. 11 is a top view thereof; and,

FIG. 12 is a bottom view thereof.
